SHIP'S COURSE BOARD

Treasure Rudder, San Francisco, Calif.

Application January 5, 1953, Serial No. 23,004

Term of patent 14 years

(Cl. D71—1)

To all whom it may concern:

Be it known that I, Treasure Rudder, a citizen of the United States of America, residing at San Francisco, in the county of San Francisco, and State of California, have invented a new, original, and ornamental Design for a Ship's Course Board, of which the following is a specification, reference being had to the accompanying drawing forming part thereof.

Fig. 1 is a front elevation of a ship's course board showing my new design.

Fig. 2 is a side elevation of Fig. 1, both sides being alike, and the back being plain.

Fig. 3 is a bottom view, and

Fig. 4 is a top view of Fig. 1.

The essential features of the design reside in the portions shown in full lines.

I claim:

The ornamental design for a ship's course board, as shown and described.

TREASURE RUDDER.
